RUDOLF WEBENDÖRFER, OF NEW YORK, N. Y., ASSIGNOR TO HIMSELF AND CARL BEITER, OF SAME PLACE.

Letters Patent No. 98,822, dated January 11, 1870.

IMPROVEMENT IN SHUTTLE FOR LOOMS.

The Schedule referred to in these Letters Patent and making part of the same.

To all whom it may concern:

Be it known that I, RUDOLF WEBENDÖRFER, of New York city, in the county and State of New York, have invented a new and useful Improvement in Looms; and I do hereby declare that the following is a full, clear, and exact description thereof, which will enable others skilled in the art to make and use the same, reference being had to the accompanying drawings, forming part of this specification.

Figure 1 represents a front view of a loom provided with my improvements.

Figure 2 is a plan or top view of the shuttle.

Figure 3 is a longitudinal section of the same.

Figure 4 is a vertical transverse section of the same.

Similar letters of reference indicate corresponding parts.

This invention has for its object to construct a positive-motion loom, in which the shuttle is not pushed ahead, and, at the same time, to do away with the belt, chain, or other constant connection with the shuttle.

The invention consists in confining, within the shuttle, the motive-power that propels the same. The loom will thereby combine the advantage of an unobstructed shuttle with that which is operated by positive motion, and will work accurately and in a reliable manner, without injury to the threads through which the shuttle passes, nor those which it carries.

The motive-power of the shuttle is obtained from two springs inserted in the shuttle, and wound up alternately at the ends of the race-way to propel it in opposite directions.

The winding-up apparatus is attached to the loom, and is put in action at the end of every stroke.

A, in the drawing, represents the shuttle of suitable form. It contains, between or outside of its sides, wheels *a a*, on which it rolls. These wheels, or, at least, one of them, should be adapted to receive the propelling-power.

The axle of one of the wheels *a* is, therefore, by toothed wheels *b b*, or by belt or otherwise, connected with a shaft, B, which is hung transversely in the shuttle.

Around the shaft B are fitted two coiled springs, C D, side by side, they being coiled in opposite directions. Their inner ends are both secured to the shaft, while their outer ends are secured to the rims of two hollow drums, E F, respectively.

The drums are hung loose on the shaft B, and have ratchet-teeth, in opposite directions, on their outer faces.

When one of the ratchet-drums is held secure by a pawl, and its spring is wound up, the spring will unwind from the inner end, and will thereby revolve the shaft, which, by its gearing-connection, will revolve the wheel *a*, and thereby propel the shuttle.

As the springs are set in opposite directions, the one will revolve the shaft B in one direction, while the other will reverse the motion, and consequently,

also, the motion of the shuttle will be reversed, as the springs are brought into action alternately.

The change of motion is produced by two pawls, *c* and *d*, which are affixed to a rock-shaft, *e*, that is hung in the shuttle.

The shaft *e* has a projecting arm, *f*.

When the shuttle arrives at one end of the race way, acted upon by the spring C in the drum E, while the pawl *c* locks said drum, the arm *f* strikes against a stationary part of the machine, and is thrown back to carry the pawl *c* off the drum E, and, at the same time, to lock the pawl *d* into the drum F.

The spring D is then wound up, and will propel the shuttle in the opposite direction, until the arm *f* is again struck, to throw the pawl *c* into, and *d* out of gear.

The winding up is produced by suitable parts of the loom. That shown in the drawing represents friction-wheels *g g*, propelled by wheels *h*, that are hung in fixed pivots, while the wheels *g* are hung on levers *i*, pivoted by the axles of *h*.

When the shuttle arrives at one end of its stroke, the lever *i* at that end is elevated by a spring, or its equivalent, and holds the wheel *g* against the drum D.

The wheel *g*, being revolved by *h*, rotates the drum, letting its pawl slip, and thereby winds the spring in such drum.

When the spring is sufficiently wound up, the lever is lowered by an arm, *l*, of the batten, or other apparatus, and thereby the shuttle is liberated. The spring then unwinds, and carries the shuttle to the other end, where the other spring is wound up in a similar manner.

I do not claim the winding-up apparatus, as that may be varied at will; neither do I claim the particular arrangement of the wheels *a*, and of their connection with the propelling-mechanism.

If desired, the two springs and their drums may be arranged upon separate shafts, in which two rods, for setting the pawls, must be used.

Having thus described my invention,

I claim as new, and desire to secure by Letters Patent—

1. The shuttle for looms, containing two springs, which propel it in opposite directions, as set forth.

2. The drums E F, containing the springs C D, for propelling a shuttle, and held in place by pawls *c d*, when the springs are to act as set forth.

3. The pawls *c d*, arranged to lock the drums E F in a shuttle, and acted upon by one or more arms, *f*, at the end of each stroke, as set forth.

4. The wheels *a a*, arranged on a shuttle, and revolved in opposite directions by the action of springs, substantially as specified.

The above specification of my invention signed by me, this 16th day of November, 1869.

Witnesses: RUDOLF WEBENDÖRFER.
